SHOE FORM

Frank P. De Witt, Skaneateles, and George Albert Kurtz, Jr., Cayuga, N.Y., assignors to Shoe Form Co., Inc., Auburn, N.Y., a corporation of New York

Filed Sept. 1, 1964, Ser. No. 393,672

8 Claims. (Cl. 12—128)

This invention relates generally to shoe forms of the type that are inserted in shoes on display to preserve their lasted shape and generally improve their appearance. More particularly, the invention has reference to a novel construction for a shoe form.

The primary object of the invention is to provide a shoe form that is highly versatile as to its application and, at the same time, is relatively inexpensive to produce. Thus, the form contemplated by the invention can be used advantageously with either high heeled or flat shoes and can also be used with soft soled shoes of the slipper type.

Another important object of the invention is to provide a shoe form having a construction that is sufficiently flexible to permit a form of a given size to be used with more than one size or width of shoe.

Still another important object of the invention is to provide a shoe form that is so constructed that it does not destroy the natural toe spring and heel spring of the shoe.

Still another important object of the invention is to provide a bottomless, flexible shoe form having a return bottom flange at the toe portion of its forepart to substantially eliminate the possibility of having the form catch on the sock lining of a shoe.

Other objects and advantages of the invention will become apparent from the following detailed description thereof, read in conjunction with the accompanying drawings which illustrate a representative embodiment of the invention for the purpose of disclosure.

In the drawings:

FIGURE 1 is a top plan view of a shoe form embodying the invention;

FIGURE 2 is a side elevation of the form of FIGURE 1 showing an alternative position of the backpart in broken lines;

FIGURE 3 is a bottom plan view of the form of FIGURE 1;

FIGURE 4 is a fragmentary side elevation of a modified construction of the shoe form;

FIGURE 5 is a fragmentary top plan view of the heel portion of the shoe form showing an indicia bearing member applied thereto;

FIGURES 6 and 7 are top plan and side elevational views, respectively, of a mold backpart with various mold foreparts being shown in broken lines to illustrate a feature of the molding method, the backpart being shown in section in FIGURE 7; and

FIGURE 8 is a vertical sectional view taken substantially along line 8—8 of FIGURE 7.

Referring now to the drawings, wherein like reference numbers designate the same part in each of the views, and with particular reference to FIGURES 1-3, reference number 10 generally designates a hollow shoe form comprised of a forepart 12 and a backpart 14. The form 10 is made of flexible, resilient material which can be transparent or appropriately colored, various types of plastic materials being suitable for this purpose. As indicated in FIGURE 3, the form is made without a bottom wall although a return flange 16 is provided at the toe portion of the forepart, by means to be presently described, to substantially eliminate the possibility of having the shoe form catch on the sock lining of a shoe as it is being withdrawn therefrom. The flange 16 is

2

also important in that it serves to strengthen the forepart of the shoe form.

The forepart 12 of the shoe form normally conforms to the last of the shoe with which the form will be used and includes a back wall 18 to which the backpart 14 is connected, the backpart being substantially narrower and lower than the forepart at the point of connection as shown. Adjacent the point of connection, the forepart is formed with a radius or rearwardly curved portion 20, and this radius and the flexible or elastic nature of the material of the form permit the backpart to be swung upwardly relative to the forepart (as indicated at 14' in FIGURE 2) without in any way damaging or stressing the form. This feature of the invention enables the shoe form to be used in high heeled as well as flat heeled shoes.

The backpart 14 of the shoe form has an inverted, substantially U-shaped cross section and increases in height at the heel portion thereof so that its flat upper surface 22 in this area is substantially flush with the upper edge of the heel portion of the shoe. Just below this surface the backpart can, if desired, be formed with an undercut or indentation 24 to receive the heel strap of a shoe. In addition, the heel portion of the backpart may be formed with a plurality of ridges and grooves 26 adjacent the lower edge to provide greater rigidity at this part of the form.

The particular configuration of the forepart back wall 18 and the inherent flexibility of the material permit limited variations in the size of the shoe form 10. This advantageous characteristic is also helped by the fact that the form is bottomless and its backpart is considerably narrower than its forepart at their point of connection. Thus, if the forepart 12 is inwardly compressed at the ball or widest part, a longer and narrower form will result as indicated by the broken line 28 in FIGURE 1. On the other hand, a rearward force on the forepart results in a shorter but slightly wider form as indicated by the broken line 30. A form of a given size can, therefore, adapt itself to minor variations in length and width, the difference in length between the lines 28 and 30 being equal to approximately one full size.

In FIGURE 4 a modified construction is shown wherein the backpart is formed in two sections 32, 34 which are hinged together as by pins 36 to facilitate insertion of the form into certain types of shoes. FIGURE 4 also illustrates how the form can be provided with a plurality of dimples or inwardly extending projections 38 for securing an indicia bearing plate 40 in position 50 beneath the upper flat surface 42. Plates 40 normally bear the name or symbol of the manufacturer of the shoes with which the shoe forms are used as indicated in FIGURE 5. Instead of snapping a separate indicia plate in position by means of the dimples 38, the plate can be molded into the form during the manufacture, or a pressure sensitive label (not shown) can simply be applied to the top of the surface 42.

FIGURES 6 and 7 illustrate a novel method of manufacturing the above described shoe form using a male mold. In carrying out the method, a mold backpart 44 is releasably secured in position on a mounting board 46 by means of locating pins 48. The backpart is adapted to be telescopically engaged at its forward end by a forepart mold having a suitable channel or recess 50 for this purpose, see FIGURE 8. As indicated, the forepart mold can be one of three common types known in the trade as toe, half and three-quarter forms designated respectively as 52, 54 and 56 in FIGURES 6 and 7. Whichever type of forepart is used for the mold, it can be dimensioned to conform to a particular manufacturer's last so that this portion of the resultant shoe form will have a custom fit with the manufacturer's

shoes. The mold backpart 44 is normally the same for each mold but its size and shape can, of course, be varied if desired. Length adjustment can be taken care of by adjusting the position of the forepart on the backpart as will be apparent.

After the mold has been set up, the shoe forms are produced from a plurality of clear or colored plastic sheets which are heated to a pliant state and then vacuum drawn into close engagement with the mold. The methods of heating and the application of the vacuum are well known in the art and need not be described in detail. Likewise, the vacuum connections to the mounting board 46 are not shown although FIGURE 7 schematically illustrates internal vacuum passages 58 in the backpart which cause the pliant plastic to be drawn inwardly to form the undercut 24 and grooves 26. The connection between passages 58 and the vacuum pump is not shown.

As best shown in FIGURE 7, the foremost point or toe portion of each forepart 52, 54 and 56 is raised slightly above the plane of the mounting board 46 because shoes are made in this manner as is well known in the art. In addition, and in accord with the present invention, the toe portion of each forepart is undercut as indicated at 60, the heated plastic material being drawn into this area by interior vacuum passages 62, FIGURE 6, which operate in the same manner as the passages 58. The undercut 60 results in the formation at 64 of the return flange 16 previously described in connection with FIGURES 1-3. After its removal from the mold, the shoe form is cut along the non-horizontal line 66 which results in the slightly raised toe portion noted above.

To remove the molded shoe form from its mold, the vacuum is shut off and the form and mold parts are lifted together from the locating pins 48. This permits the forward end 68 of the mold backpart to drop out of the recess 59 in the forepart and be removed from the form by means of a forward and downward motion. Thereafter, the forepart can be easily removed from the form by means of a rearward and downward motion, and the cutting on the line 66 can then take place.

The shoe form of the invention can also be produced in a cavity or female mold, or it can be produced by means of coacting male and female molds. The male mold and method described, however, lend themselves to low cost semi-automatic production and have many advantages, the most important of which is the ease with which the mold or a portion thereof can be changed. Obviously, a plurality of molds can be mounted on the mounting board so that a plurality of shoe forms are simultaneously produced from a single sheet of plastic.

From the foregoing description it will be apparent that the invention provides a novel and very versatile shoe form and method of manufacture. As will be understood by those familiar with the art, the invention can be embodied in other specific forms without departing from the spirit or essential characteristics thereof. The embodiment disclosed is therefore to be considered in all respects as illustrative rather than restrictive, the scope of the invention being indicated by the appended claims.

What is claimed is:

1. A molded shoe form of flexible resilient material comprising a hollow bottomless forepart having a trans-

versely disposed back wall, and a hollow bottomless backpart connected at its forward end to said back wall, said backpart being substantially narrower and lower than said forepart at the point of connection, said transversely disposed forepart back wall being formed with a radius adjacent the point of connection to facilitate upward bending of the backpart relative to the forepart to enable the form to be used in a high heeled shoe.

2. A shoe form as defined in claim 1 wherein said forepart is formed with a return bottom flange at the toe portion thereof to strengthen the form and prevent it from catching on the sock lining of the shoe.

3. A molded shoe form of flexible resilient material comprising a hollow forepart having a substantially flat back wall, and a hollow backpart connected at its forward end to said back wall, said backpart having an inverted U-shaped cross section and being substantially narrower and lower than said forepart at the point of connection, said forepart back wall being formed with a rearwardly curving portion adjacent its point of connection with said backpart to facilitate upward bending of the backpart relative to the forepart to enable the form to be used in a high heeled shoe, said forepart being compressible laterally to permit limited width and length variations in the form.

4. A shoe form as defined in claim 3 wherein said forepart is formed with a return bottom flange at the toe portion thereof to prevent the form from catching on the sock lining of the shoe.

5. A shoe form as defined in claim 3 wherein said backpart increases in height at the heel portion thereof so that the upper surface of the heel portion is substantially flush with the upper edge of the heel portion of the shoe.

6. A shoe form as defined in claim 5 wherein said backpart is formed in two parts hinged together to facilitate insertion of the form into a shoe.

7. A shoe form as defined in claim 5 wherein said backpart is formed with an undercut portion in the rear wall of the heel portion thereof for engagement with the heel strap of a shoe.

8. A shoe form as defined in claim 5 wherein said backpart includes means for securing an indicia bearing member adjacent the upper surface of its heel portion.
